CIRCULAR MOTION MECHANISM

John P. Putnam, Boston, Mass., assignor to The
Reece Button Hole Machine Company, Boston,
Mass., a corporation of Maine

Application November 7, 1941, Serial No. 418,209

10 Claims. (Cl. 74—1)

This invention relates to circular motion mechanisms and more particularly to circularly extensible and contractible, divisional structures.

Circularly extensible and contractible, divisional structures have been used heretofore. They have, for instance, been associated with extensible and contractible, flexible scales for the intended purpose of varying the graduations of the scale in constant ratio with the extension and contraction of these structures. An example of such an application of a circularly extensible and contractible, divisional structure is given in a prior application Serial No. 393,517, filed May 15, 1941. These prior structures have, however, considerable play or lost motion in the several divisions thereof, with the result that the latter do not expand or contract as uniformly as is required, for instance, of the graduations of a scale for accurate, instead of only approximate, readings.

The present invention has for its object the provision of a circularly extensible and contractible, divisional structure in which the play in the several divisions is for all intents and purposes eliminated so that the divisions expand or contract most uniformly.

The invention will best be understood from the following description of an illustrative embodiment thereof shown in the accompanying drawings in which:

Fig. 1 diagrammatically illustrates a straight line mechanism which forms the basis for the present invention.

Figs. 2 and 3 are diagrammatic views illustrative of the present invention.

Fig. 4 is a fragmentary plan view of mechanism embodying the invention.

Fig. 5 is an enlarged plan view, partly in section, of an instrument in which the present invention finds, by way of an example, practical application.

Fig. 6 is a similar view of the instrument with certain parts thereof removed for better illustration of the applied invention.

Fig. 7 is a side elevation, partly in section, of the instrument, the section being taken substantially on the line 7—7 of Fig. 5.

Fig. 8 is a fragmentary section taken substantially on the line 8—8 of Fig. 6.

Referring to the drawings and particularly to Fig. 1 thereof, there is shown a straight line mechanism which forms the basis for the present invention. This mechanism comprises two links 8 and 9 and a rocker 10. The links 8 and

9, which are of equal length, are rotatable about fixed pivots *d* and *c*, respectively, and are pivotally connected with the rocker 10 at *a* and *b*, respectively. The point *p* of the rocker is spaced from the pivots *a* and *b* at an equi-distance which is equal to the length of either link 8 or 9. The length of the side of the rocker opposite the point *p* is immaterial. With these conditions prevailing, the point *p* of the rocker 10 will move in an approximately straight line passing through the fixed pivots *c* and *d* when the mechanism 8, 9, 10 is rocked in either direction about the fixed pivots *d*, *c*. The limits of the approximate straight line motion of the point *p* are adjacent the fixed pivots *c* and *d*, respectively (see dotted and dot-and-dash line positions of mechanism 8, 9, 10). The longer the links 8, 9 and the sides of the rocker 10 which meet at the point *p* are in comparison to the distance between the fixed pivots *d* and *c*, the more closely will the point *p* travel in a straight line. The straight line mechanism is applied to the present invention in the manner illustrated in Figs. 2 and 3. In Fig. 2, the links 8 of two straight line mechanisms of identical dimensions are formed by portions of two arms 11a and 11b which are turnable about fixed pivots *d*, respectively, while the links 9 are rotatable about fixed pivots *c*, respectively. On turning either arm 11a or 11b about its fixed pivot *d*, the point *p* of the corresponding mechanism will travel on an approximately straight line. If the parts of the two identical straight line mechanisms assume the same relative disposition, as shown in full lines in Fig. 2, it is evident that equal angular displacement of the arms 11a and 11b from their full line position (Fig. 2) into the dotted line position, for instance, will result in identical displacement of the mechanisms. Conversely, equal displacement of the mechanisms from the identical full line positions into the dotted line positions in Fig. 2, for instance, will result in equal angular displacement of the arms 11a and 11b. These 25 functions of identical straight line mechanisms are utilized in the construction shown in Fig. 3. Here, three arms 11a, 11b and 11c are rotatable about a common axis *d'*, and the arms 11a and 11b are associated with the same identical 30 straight line mechanisms shown in Fig. 2. The third arm 11c has a common pivotal connection *c'* with the links 9, 9 of the straight line mechanisms. The rocker 10' is provided with a pin 12 whose center is the same as the point *p* of the 35 mechanism which includes the arm 11a in Fig. 55

2, while the rocker 10'' is provided with a slot 13 in which the pin 12 is received. The slot 13 extends transversely to a straight line passing through the pivots c' and d'. With these conditions prevailing, and with the arm 11c, for instance, held stationary, a turning of either arm 11a or 11b in either direction through a certain angle will result in a turning of the other free arm in the opposite direction through the same angle. This is due to the connection 12, 13 between the rockers 10' and 10'' of the straight line mechanisms which compels the latter to be equally displaced when either one is displaced. By the same token, the arm 11a, for instance, may be held stationary and arm 11c turned in either direction through a certain angle, in which case the arm 11b will be turned in the same direction through twice said angle. Conversely, with the arm 11a held stationary, the arm 11b may be turned in either direction through a certain angle, in which case the arm 11c is turned in the same direction through one-half said angle. Also, the arm 11a, for instance, may be dispensed with and the rocker 10' rotatably mounted on a fixed pivot a'. In that case, either one of the arms 11b or 11c may be turned, and such turning will have the same result on the other arm as described in the two preceding examples. Since both, the pin 12 and the slot 13, travel in a common, approximately straight path which extends through the pivots d' and c' and hence, radially of the common turning axis of the arms 11a-c, it is evident that whatever relative motion there is between the pin and slot transversely to their common radial path is very small. Of course, when the pivots a', a' and c' lie in the longitudinal axes of the arms 11a, 11b and 11c, respectively, as they do in Fig. 3, the arms 11a-c are equi-angularly spaced in any angular relative disposition.

The construction shown in Fig. 3 has for all intents and purposes no play between the various parts thereof. All the connections between the parts, except the pin and slot connection 12, 13, are non-floating pivot connections in which all play can be eliminated without difficulty. As mentioned above, the pin 12 and slot 13 move together in a near linear path and have very little relative movement transversely thereto, so that an accurate fit of the pin without play in the slot in any position on said linear path is not difficult to attain. Hence, the pin and slot connection 12, 13 has for all intents and purposes no more play than a non-floating pivot connection. In the absence of any appreciable play between the parts of this construction, the reaction of the slightest turning movement of one of the arms 11a-c upon the other arms is instantaneous and not delayed by any lost motion.

Fig. 4 illustrates a preferred coordination of the parts where more than three radial arms are angularly extensible and contractible. Since the coordination of the parts may be the same for any number of radial arms over three, there are shown, for simplicity's sake, only four radial arms 14a-d which differ from the arms 11a-c in Figs. 2 and 3 by being longitudinally slotted at 15. The arms 14a-d, which are turnable about the common axis d'', are equally axially spaced from each other so that the arm 14a is the lowermost, and the arms 14b, 14c and 14d are progressively higher. Pivots mounted at a'

on the arms 14a-d remote from their longitudinal axes x-x are the rockers 10a to 10d, respectively, and coaxially pivotally mounted at c'' on the arms 14b and 14c, respectively, are the link pairs 9a, 9c and 9b, 9d, respectively, which are pivotally connected at b'' with the rockers 10a, 10c and 10b, 10d, respectively. The farther the pivot mountings a'' of the cooperating rocker pairs 10a, 10c and 10b, 10d, respectively, 10 are spaced from each other (by pivotally mounting said rockers at the lateral extremities of their respective arms 14a-d), the longer will be the links 9a-d and the sides of said rocker pairs which converge upon their respective floating 15 pivot connections 16', 17' and 16, 17, and the more closely will the pivots 16 and 16' travel in straight paths radially of the pivot d''. The rocker 10d is situated in the axial space between the arms 14c and 14d, while the rocker 10b, 20 which has the floating pivot connection 16, 17 with the former rocker, is situated in the axial space between the arms 14b and 14c. The pivot 16 of the connection 16, 17 extends through, and travels in, the longitudinal slot 15 in the arm 14c substantially radially of the pivot d''. Also situated 25 in the axial space between the arms 14c and 14d, though in planes other than that of the rocker 10d, are the links 9b and 9d, respectively. The rocker 10c is, like the rocker 10b, situated in the axial space between the arms 14b and 14c, but below said rocker 10b so as not to interfere with the floating pivotal connection 16, 17 between the latter and the rocker 10d. The rocker 10a, which has the floating pivotal connection 16', 17' with the rocker 10c, is situated 30 in the axial space between the arms 14a and 14b. The pin 16' of the connection 16', 17' extends through, and travels in, the longitudinal slot 15 in the arm 14b substantially radially of the pivot d''. Also situated in the axial space 35 between the arms 14b and 14c, though in planes other than that of the rockers 10b and 10c, are the links 9a and 9c, respectively. In thus grouping the various parts of the construction none 40 of these parts will interfere with the movements of the other parts, and the angular extension and contraction of the arms 14a-d is solely limited by the possible extent of travel of the pins 16 and 16' in the longitudinal slots 15 of the 45 arms 14c and 14b, respectively. The described grouping of the parts may be repeated for any desired number of arms, and the angular extension and contraction of the latter is, as in the case of four arms (Fig. 4), solely limited by the 50 possible extent of travel of the pins of the floating pivotal connections in the longitudinal slots in the arms. Inasmuch as the longitudinal axes x-x of the arms 14a-d are also symmetrical axes, and the pivot mountings c'', c'' of the links 55 9a, 9c and 9b, 9d, respectively, lie in the symmetrical axes of the arms 14b and 14c, respectively, and the pivot mountings a'' of the rockers 10a-d are equally spaced from the symmetrical axes x-x of their respective arms 60 14a-d, it follows that the arms 14a-d are equi-angularly spaced in any relative angular disposition.

In analyzing the construction shown in Fig. 4, each rocker 10a-d may be considered a link 65 which forms with its respective, connected link 9a-d a relatively rotatable link pair. The pairs of relatively rotatable links connect the angularly spaced arms, respectively, with the adjacent opposite arms, respectively, while the floating pivotal connections between the rockers serve

as means for guiding the links of the several pairs for relative rotation so that the intended relative turning movements of the arms may take place.

An example of one of many practical applications of the present invention is illustrated in Figs. 5 to 8. The instrument there illustrated is a watch or similar time piece adapted primarily for use in connection with the navigation of aircraft, and is in many respects like the time piece shown and described in said prior application, Serial No. 393,517, filed May 15, 1941. Thus, the dial 18 of the time piece (Fig. 5) has a central portion 19 graduated in the usual manner in hours and minutes and over which are movable the usual hour and minute hands 20 and 21, respectively, and surrounding and disposed concentric with the portion 19 is an annular time scale 22, likewise graduated in minutes and hours, although preferably on a different basis, and movable over and in cooperation with which is a third hand 23 whose timing, or speed of movement, corresponds to the graduations of said scale 22, and whose operating mechanism includes means whereby it can be returned to zero position, at any time and started from this position at the will of the operator. Also surrounding, and disposed concentric with, the time scale 22, in a position likewise to cooperate with the hand 23, is an arcuate, extensible and contractible, combined distance and speed scale indicated as a whole at 24, carrying distance or speed interval indicia elements 26, identified at convenient points by suitable numerals and constituting graduations whose spacing varies with the extension and contraction of the scale as a whole. One end of the scale 24, namely, what may be considered the zero end thereof, is fixed adjacent the zero point of the scale 22, and its opposite end is connected to a bezel or ring 25 (Figs. 7 and 8) rotatably mounted on the watch or clock case 27, whereby rotation of said bezel with respect to said case and the dial 18 will cause circumferential extension or contraction of the scale 24, thereby causing the indicia elements 26 thereof to register with the graduations of the scale 22 in variable relationship. In use, the bezel is turned to cause the index element 26 of the scale 24 corresponding to the assumed or estimated ground speed (e. g., as shown in Fig. 5, 50 miles per hour) to register with the one hour point on the scale 22. The hand 23, being in zero position, is started from said position at the instant of departure. Thereafter, the hand 23 will, at any moment, indicate on the scale 22 the distance traversed from the point of departure at that moment if the initially assumed ground speed for which the instrument has been set is correct. At the time of arrival, however, over a recognizable landmark whose distance from the point of departure is known, the pilot can, if necessary, correct the setting of the instrument by turning the bezel 25 to bring said known distance on the scale 24 into register with the position of the hand 23 at that time, whereupon the actual ground speed will be indicated on the scale 24 opposite the one hour point on the scale 22, and the hand 23 will thereafter, at all times, correctly indicate on the scale 24 the distance covered.

The construction and operation of the instrument as thus far outlined are or may be substantially as more fully described in the prior application above referred to. The present invention is applied for guiding and controlling the arcuate extension and contraction of the scale 24 to

the end that such extension and contraction shall be accurately proportionate throughout, the variation of the spacing of the indicia or graduations shall be in constant ratio to the extension and contraction of the scale as a whole and the several indicia be accurately held in substantially fixed, invariable positions for a given setting of the scale 24.

The dial 18 is supported by, and in spaced relation to, a base plate 30 carried by the watch or clock case 27 as follows. Secured, as by screws 31 (Fig. 6), to the base plate 30, in a region below a portion of the scale 22 angularly remote from the zero end thereof, is the lower end portion 32 of an angular bracket member having an upwardly inclined portion 33 (see also Fig. 7) supporting a portion 34 disposed parallel to the portion 32, plate 30, and dial 18 in a region below the scale 22 (and scale 24) adjacent the zero end thereof, said bracket portion 34 terminating in an upwardly or outwardly turned end 35. Extending between the base plate 30 and dial 18 is a central post 36 formed hollow to receive the nested arbors of the several hands of the timepiece. Extending between the upper or outer end of the post 36 and the upwardly or outwardly turned end 35 of the bracket portion 34, is a bridge member 37 by which the dial 18 is supported and to which it is secured in any suitable manner. Rotatably mounted on the post 36 are the inner ends or hub portions 38 of radial arms 14 (similar to those shown in Fig. 4), said arms being disposed in a superposed series, and their several hub portions being separated by washers or spacers 40, as shown in Fig. 7. The equi-angularly spaced arms 14e, 14f, 14g—14n (Fig. 6) are interconnected by links 9 and rockers 10 in the same manner as the arms in Fig. 4, so that they are relatively rotated in equiangularly spaced relationship when any one of the arms is turned. More particularly, the links 9 and rockers 10 are situated in the axial spaces between the arms 14e, 14f, 14g—14n in the manner explained in connection with Fig. 4, so that the angular extension and contraction of these arms is solely limited by the possible extent of travel of the pins 16 in the longitudinal slots 15 of said arms. The first or lowermost rocker 10e in Fig. 6 is rotatably mounted on a fixed pivot a'' on the base 39 so that all arms 14e—n are turned when any one of said arms is turned. With the arms 14, links 9 and rockers 10 thus coordinated, the arms 14e, 14f, 14g—14n are turned in equi-angularly spaced relation if any one of these arms is turned. The outer ends of the arms 14 are guided on the outer margin of the base plate 30 by rollers 41 carried by angular extensions 42 at said outer ends which are of suitable lengths, respectively, to bring the axes of the several rollers into the proper common plane.

As in the prior application aforesaid, the scale 24 as herein shown comprises a lazy-tongs structure, being in the present instance composed of a plurality of sections of equal length joined end to end to form the complete structure. The index element 26a at the zero end of the scale is secured to the base plate 30 by a pair of bolts 50 and 51 formed with shoulders 52 (Fig. 7) whereby said element is suitably spaced from said plate. Similarly, each of the arms 14 has secured thereto, adjacent its outer end and at the same spacing from the base plate 30 as the index element 26a, an index element 26b, 26c, 26d, 26e—26n by means of shouldered bolts 50b—50e—50n and 51b—51e—51n. The bolt 51n for securing the

index element 26n to the arm 14n at the free end of the lazy-tongs structure, i. e., the end opposite the zero end thereof, has an extension 53 (Fig. 8) received in a socket 54 formed in the inner face of the bezel 25. The end link 55a (Fig. 6) at the zero end of the lazy-tongs section 24b at the zero end of the scale 24 is pivoted on the end of the bolt 51. The link 55n at the other end of the lazy tongs structure is pivoted on the end of the bolt 51n. The links 55 at the contiguous ends of adjacent or successive sections of the structure have common pivotal connection to the respective arms 14 by means of the bolts 51b, 51c, etc.

The angularly movable arms 14, connected as just described with the lazy-tongs structure at the points of junction of the equal sections thereof, and therefore connected with the structure as a whole at equally spaced points circumferentially thereof, serve to guide the arcuate expansion and contraction of said structure or scale, and since the angular approach and separation of adjacent arms is in constant ratio throughout the series of arms, the equal expansion of the scale throughout its length will be preserved.

I claim:

1. Mechanism comprising more than two angularly spaced, relatively coaxially turnable arms; and a device relatively turning said arms equal angular amounts on turning one arm, said device comprising pairs of relatively turnable links connecting said arms, respectively, with the adjacent opposite arms, respectively, and means guiding the links of each pair for relative turning movement.
2. Mechanism as set forth in claim 1, in which the link pairs are identical and their corresponding pivot connections, respectively, with the arms are equidistant from the turning axis of said arms.
3. Mechanism as set forth in claim 1, in which said link guiding means are carried by some of said links.

4. Mechanism comprising more than two angularly spaced, relatively coaxially turnable arms; and a device relatively turning said arms equal angular amounts on turning one arm, said device comprising identical pairs of relatively turnable links connecting said arms, respectively, with the adjacent opposite arms, respectively, the corresponding pivot connections, respectively, of said

link pairs with the arms being equidistant from the turning axis of the latter, and means equi-angularly spacing the links of each pair, said means also equally varying the angle between the links of each pair on turning one arm relative to the other arms.

5. Mechanism comprising more than two angularly spaced, relatively coaxially turnable arms; and a device relatively turning said arms equal angular amounts on turning one arm, said device comprising pairs of relatively turnable links connecting said arms, respectively, with the adjacent opposite arms, respectively, and connections between opposite links of said pairs, respectively, said arms, links and connections being so coordinated that the latter move in paths approximately radial of the turning axis of said arms on relative turning movement of the latter.

6. Mechanism as set forth in claim 5, in which said connections are pivotal connections floatable transversely to said radial paths.

7. Mechanism comprising at least three angularly spaced arms relatively turnable about a common axis; two rockers pivotally mounted on the outer arms, respectively, at an equi-distance from said common axis; two links, each of a length equal to said equi-distance, connecting said rockers, respectively, with a common point on the intermediate arm; and a floating pivotal connection between said rockers including a pin on one rocker spaced at said equi-distance from the pivot mounting of said one rocker and the turning point thereon of the link connected therewith.

8. Mechanism as set forth in claim 7, in which said floating pivotal connection further includes a slot in the other rocker receiving said pin and extending transversely to a direction radially of said common axis.

9. Mechanism as set forth in claim 7, in which the outer arms have lateral outward extensions on which the rockers, respectively, are pivotally mounted remote from the longitudinal axes of said arms.

10. Mechanism as set forth in claim 7, in which said arms are axially spaced and said rockers interposed in the axial spaces, respectively, between said arms, and said intermediate arm has a longitudinal slot through which said pin extends.

JOHN P. PUTNAM.
